UNITED STATES PATENT OFFICE.

SYDNEY SMITH, OF DETROIT, MICHIGAN, ASSIGNOR TO THE STUDEBAKER CORPORATION, A CORPORATION OF NEW JERSEY.

METHOD OF MAKING AND ENAMELING AUTOMOBILE BODIES.

Application filed August 2, 1919. Serial No. 315,034.

To all whom it may concern:

Be it known that I, SYDNEY SMITH, a citizen of the United States of America, and resident of Detroit, in the county of Wayne and State of Michigan, have invented certain new and useful Improvements in Methods of Making and Enameling Automobile Bodies, of which the following is a specification.

10 This invention consists in a method of process by which automobile bodies may be constructed with a wooden frame and a metallic sheathing and an enamel coating or finish applied to the sheathing, said finish 15 being treated by the application of heat, i. e. what is known as the "baking" operation. It also embraces the resultant article of manufacture.

Automobile bodies are usually constructed 20 by first building up a frame work of wood, and then overlaying said framework with metal sheathing bent and formed to fit over the wooden frame. The sheathing is then treated with a suitable finish. It has long 25 been recognized that the most lustrous, as well as the most durable finish, is that known to the trade as the "baked" finish, which results from the application of a plurality of coats of enamel subjected to a 30 baking process. During the carrying out of this process, however, the temperature required to properly bake the enamel is usually in the neighborhood of 300° F., and, when it is endeavored to impart a 35 baked finish to an automobile body, it is found that this temperature is so excessive that the wooden frame is very seriously affected. Heretofore, attempts to this end have resulted in so depreciating the wood 40 of the frame that it became charred, warped, twisted and distorted and the glue by which the parts of the frame were united melted, with the result that the frame was loose jointed and squeaked and rattled when a 45 vehicle thus manufactured was put to subsequent use.

For these reasons it has been considered impractical to provide a car body with the baked finish, through the inability of the 50 wooden elements thereof to withstand the heat required. As a compromise it has been the usual practice, in car finishing to finish such all-metallic parts as the fenders, mud guards, etc. with the baked finish, i. e. employing said process wherever possible on

all-metallic parts, and to finish the body, where this process had proven impractical, with the well-known "float" process, which consists in successively applying fluid coatings and permitting the same to dry. A 60 car thus finished appears very attractive and neat when new and those parts of the car which have received the baked finish retain their attractive appearance for a long time, but the parts of the car which had been treated with the float process, rapidly deteriorate, lose their luster, and are highly sensitive to scratches so that, in a relatively short time, the body of such a car will appear dull and unsightly, while the 70 all-metallic parts which have received the baked finish, will retain their luster. Another disadvantage inherent in the employment of the float process is the question of cost, it being well recognized that the float 75 process, besides being much inferior to the baked finish is much more costly. In spite of these considerations, however, it is the common practice at the present time to employ, as a compromise, the combination of 80 both processes in the manufacture of automobiles.

I have been involved in experimentation and research in an endeavor to discover a method whereby the superior baked finish 85 might be applied to car bodies without deleterious effects on the wooden frame thereof and, as a result I have found that if the wooden frame of the body is treated according to a certain process prior to the application of the enamel baking process, it 90 may be so conditioned as to properly withstand the relatively high temperatures required in the carrying out of said baking process, and that the body portion of the 95 automobile may thereafter be dealt with during the finishing operation in substantially the same manner as the all-metallic parts of the car without suffering ill effects due to the application of the baking heat.

The process of treating wood in such manner as to adapt it to this use forms the subject-matter of my co-pending application, Serial No. 315035 filed Aug. 2nd, 1919, 100 wherein the consecutive steps in the carrying out of the method are set forth in detail and it is not considered necessary to reiterate the process here. The method of this invention does not consist in the treatment of the wood but is directed rather to 110

the manufacture of automobile bodies through the fabrication of a frame treated in the manner described in my co-pending application, the application of sheathing to such a frame, and the subsequent finishing of the whole.

10 The accompanying drawings illustrate the manner in which a well known form of automobile body frame may be prepared for treatment by the method of this invention.

15 In carrying out the method of this invention in one of its practical forms, the wooden elements 1 of the frame are cut to shape and size and assembled in the usual 20 way. This assembly may be carried out through the employment of bolts and screws 2 supplemented by glue but, if desired, the glue may be omitted. If glue is employed, I prefer to use a glue which is especially 25 prepared to possess such qualities that, when once set or hardened, it will not respond, or be affected by heat. Of course, different kinds of glue may be employed, but I have found that ordinary hot glue 30 proves quite satisfactory if there is added thereto a small quantity of bi-chromate of potash crystals and a little water. The glue is heated, and the crystals added whereupon the glue is immediately applied 35 while hot, since such glue, when cold, is permanently set or hardened. The parts of the frame are thus glued together and the glue is preferably reinforced by screws or bolts so that at the conclusion of this step 40 in the process the frame is complete in itself and is in the form to receive the sheathing.

45 After the framing operations are completed as described temporary braces 3 are preferably secured across the door openings in order that the frame may be held in proper shape during the successive operations thereon and these braces are preferably so positioned that they may be left 50 in place during the paneling and finishing operations. The braces referred to, while an assistance, are not, however, essential and may be dispensed with without departing from this invention.

55 The frame assembled as described is now subjected to the treatment described in my co-pending application, which conditions the completed frame to be capable of withstanding temperatures of the baked finish process without deterioration. If desired, the wooden elements of the frame may be treated before assembling them to form the frame. At the conclusion of the treatment on the completed frame the wooden elements thereof may be found to have contracted slightly and it is desirable at this 60 stage, that the screws and bolts 2 thereof be gone over and taken up to compensate for any slight contraction which may have 65 occurred. The sheathing is now applied to

the frame in the usual manner and provided with the usual coating or coatings which are properly surfaced, finished and baked, after the well-known baked process. During the carrying out of this process the 70 temperature may be safely raised to upward of 300° F. and this temperature may be sustained for the proper length of time without fear of destroying the wood fibre of the frame which, because of their previous 75 treatment, are rendered immune from deterioration under such temperatures.

80 In carrying out the finishing operation good results are obtained by first washing the body thoroughly with gasoline and sanding the high spots with fine emery cloth. Both the inside and outside may then be flowed with Oxford Low Baking Primer or any other suitable primer, and the whole baked for approximately an hour 85 at 300° F. For second and third and subsequent coats any suitable finishing enamel may be applied, each coat being baked for an hour at about the same temperature, although the last coat should be baked slightly 90 longer. This specific procedure has been found to give good results, although the present invention is manifestly not restricted to the details enumerated, as different temperatures and coatings may be employed and any number of these coatings 95 may be applied as desired, in accordance with the finish sought. The body treated and finished as specified possesses all of the advantages of the baked finish as regards 100 its luster and durability and the frame of said body remains firm and rigid and has tight joints. Charring, deterioration, or alteration of the wood and frame does not occur and actual employment of the process 105 had conclusively shown that the frame construction will not work loose or rattle but will retain its substantially homogeneous condition under the hard usage of the road.

110 Having thus fully described the invention, what I claim as new and desire to secure by Letters Patent is:

1. In the art of automobile body making, the method which consists in fitting together and assembling wooden frame elements and securing them in position by mechanical means, thereafter treating the wood of the assembled frame in such manner as to raise the heat resisting qualities of the wood to a point where it will withstand the heat necessary for imparting a baked finish to a metal sheathing to be subsequently applied thereto, and then tightening the mechanical means, to take up the contraction resulting from said treatment. 115

120 2. In the art of automobile body making, the method which consists in assembling wooden frame elements through the employment of a heat resisting glue and mechanical means to form a body frame, 125

thereafter treating the wood of the assembled frame in such manner as to raise the heat resisting qualities of the wood to a point where it will withstand the heat necessary for imparting a baked finish to a metal sheathing, and finally tightening the mechanical means to take up the contraction resulting from such treatment.

3. In the art of automobile body making, the method which consists in assembling frame elements through the employment of glue and mechanical compression means to form a body frame, thereafter treating the wooden elements of the assembled frame to raise the heat resisting qualities thereof, then tightening said compression means to compensate for contraction in the frame during the treatment thereof, thereafter applying a metal sheathing to the thus treated frame and finally applying a baked finish thereto.

4. In the art of automobile body making, the method which consists of assembling frame elements through the employment of glue and mechanical compression means to form a body frame, thereafter treating said frame thus assembled in a manner to raise the heat resisting quality of the wood of which it is composed, and tightening said mechanical compression means to compensate for contractions in said frame during said treatment thereafter applying a metal sheathing to said frame and treating said sheathing with an enamel coating, and ap-

plying heat to such enameled coating of 35 a sufficient degree to fix the same.

5. A new article of manufacture comprising an automobile body frame consisting of wooden elements united by glue interposed between the contacting faces thereof, said wooden elements being so treated by the application of enamel and heat as to raise the same to a high point of heat resistance, the said wooden frame being then subjected to mechanical pressure to 45 compensate for contraction during the operation of said last mentioned process.

6. A new article of manufacture comprising an automobile body frame consisting of wooden elements united by glue 50 interposed between the contacting faces thereof, said wooden elements being so treated by the application of enamel and heat as to raise the same to a high point of heat resistance, the said wooden frame being then subjected to mechanical pressure 55 to compensate for contraction during the operation of said last mentioned process, said frame being enclosed in a sheathing of metal finished with enamel treated by a 60 baking process.

Signed by me at Detroit, Michigan, U. S. A., this 29th day of July, 1919.

SYDNEY SMITH.
